UNITED STATES PATENT OFFICE.

JOSEPH W. FREEMAN, OF COLUMBUS, OHIO, ASSIGNOR OF ONE-HALF TO COLONEL E. BRIGHT, OF COLUMBUS, OHIO.

COMBINED CASKET AND GRAVE-VAULT.

1,298,688.

Specification of Letters Patent.

Patented Apr. 1, 1919.

Application filed July 24, 1916. Serial No. 110,859.

To all whom it may concern:

Be it known that I, JOSEPH W. FREEMAN, a citizen of the United States, residing at Columbus, in the county of Franklin and State of Ohio, have invented certain new and useful Improvements in Combined Caskets and Grave-Vaults, of which the following is a specification.

This invention relates to combined caskets and grave vaults of the type wherein a casket of conventional appearance may be very readily transformed into a grave vault when the remains reach the cemetery.

The main object of this invention resides in the combination between the casket body and the hood for transforming this casket body into a grave vault, the hood being arranged in such relation that it closely fits the sides of the casket when it is desired to transform the same into a grave vault. In this connection, my invention also resides in the provision of coöperating shoulders between the hood member and the casket body, whereby a seal is formed to make the confinement within the casket body complete.

Other objects of my invention reside in the particular arrangement of hood and its specific relation with the casket body. These detailed constructions will become more apparent after a description of the accompanying sheets of drawings, in which similar characters of reference designate corresponding parts, and in which:

Figure 1 is a perspective of my invention showing the same in the form of a grave vault.

Fig. 2 is a cross section, taken through the lower portion of the casket body, showing the manner of attachment of the handles.

Fig. 3 is a transverse cross sectional view taken along the line 3—3 of Fig. 1.

Fig. 4 is a horizontal sectional view taken along the line 4—4 of Fig. 3.

Fig. 5 is a detailed view showing one of the corner constructions.

In the present embodiment, the casket body is made of corrugated sheet metal with the coverings, moldings and handles attached thereto in such manner that the metal body is not punctured. In the drawings, this corrugated sheet metal body is designated by the reference numeral 1 and is shown as being made from a blank having a bottom 2 and side walls 3 bent at right angles through the corrugations to the bot-

tom 2. The ends 4 are likewise bent at right angles to the base and their vertically extending edges joined to form a lock joint of the type illustrated in Fig. 5. In this joint the vertically extending edges of both the sides and ends are bent to be parallel with each other as is shown at 5, then bent laterally as at 6 and then again bent as shown at 7 to be parallel with the sides 5. These edges are securely rolled into firm holding engagement and if desired, the joint may further be soldered. In this way, a container having a bottom and two sides and two ends with an open top, is provided. In order to

secure the handles 8 in position without puncturing the casket body, I have provided two sets of straps 9, which embrace the lower portion of the casket body and which straps are provided with tapped holes along their tops, which tapped holes are provided to suitably hold nuts 10 in position, as is shown. To these nuts, the handles 8 are then secured and it will, therefore, be apparent that the handles may be attached without puncturing the casket body. The outside trimmings are

then attached to the casket body and this is preferably accomplished by attaching a base unit such as cardboard 11 directly to the outside walls of the casket body and then gluing or otherwise securing a cloth covering 12 in position. A reinforcement member 13 is located adjacent the upper edge and extends completely around the top of the casket. This reinforcement member is pref-

erably made of a metallic sheet bent to present a vertical leg 14, an inwardly projecting horizontal leg 15, a down-standing leg 16, an additional horizontal leg 17 and a final inclined leg, as is shown at 18. The horizontal leg 17 forms a shelf upon which the wood member 19 rests, which member 19 is designed to coöperate with the lid 20 to form a seat therefor and to prevent the emission of metallic sounds when the lid is lowered. The horizontal leg 15 forms a shelf or shoulder for coöperating with the hood member as will be presently described. The lid 20 is hingedly mounted to the casket body, as is shown at 21 and this mounting is located inwardly of the shoulder portion 15 to permit the hood to be moved into operating position.

The hood itself is formed with a top, depending sides and ends and an open bottom. The top portion is designated by the ref-

110

erence numeral 22 and it will be noted that this top is made of corrugated sheet material, whose ends and sides are bent downwardly for a slight distance. The remaining portion 5 of the hood is made of plain material, inasmuch as the greatest strain is placed upon the top and, therefore, corrugated metal has been resorted to in order to obtain the desired rigidity. These sides and ends 10 are designated by the reference numeral 23 and each is given a horizontal bend designated 24 to form a shoulder to coöperate with the shoulder 15 of the casket body. These two shoulders preferably have the gasket 15 placed between them, in order to more perfectly effect a seal. The horizontal portions 24 of the sides and ends are then given an inclined bend as shown at 26 and then an additional horizontal bend 27, which latter portion forms the means of attachment 20 to the top portion 22. The meeting edges between the corrugated and plain materials may be soldered in order to render them air tight and the corner portion of each are 25 formed to present a joint similar to that shown in Fig. 8 which has been described in connection with the corners of the casket body itself. It will be noted that the depth of the sides and ends 23 is such that when 30 the two shoulders 15 and 24 are in coöperative position, the lower edges of the sides and ends lie directly above the handles 8 and, therefore, it is not necessary that these handles should be removed when the hood is 35 moved to its operative position. The weight upon the top of the hood brings it into firm holding engagement with the gasket 25 and thus water is prevented from entering the casket, since it is only possible that this

water enter the space between the sides of 40 the hood and the casket body for a slight distance.

What I claim, is:

1. A combined casket and grave vault comprising a casket body, a lid thereon, 45 smaller than the top of said body to thereby form a peripheral shoulder around said body, and a hood having depending sides and ends and an open bottom to be placed in position over the outside of the casket body, 50 said sides being formed with an inward bend adjacent their tops to form a coöperating shoulder and then bent upwardly and a top adapted to rest upon the upwardly bent sides of said hood. 55

2. A combined casket and grave vault comprising a casket body, a lid thereon smaller than the top of said body to thereby form a peripheral shoulder around said body, and a hood having depending sides 60 and ends and an open bottom to be placed in position over the outside of the casket body, the top portion of said hood being of corrugated material and the depending sides and ends lying adjacent the sides and ends of 65 the casket body being of flat material, the sides being formed with an inward bend where the top joins them to form a coöperating shoulder and then an upwardly inclined bend to rest against the underside 70 of the corrugated top.

In testimony whereof I affix my signature in presence of two witnesses.

JOSEPH W. FREEMAN.
